M. H. COHEN,
COMBINED GAS BURNER AND WATER HEATER,
APPLICATION FILED NOV. 12, 1913.

1,107,088.

Patented Aug. 11, 1914.

UNITED STATES PATENT OFFICE.

MAURICE HERBERT COHEN, OF BROOKLYN, NEW YORK.

COMBINED GAS-BURNER AND WATER-HEATER.

1,107,038.

Specification of Letters Patent. Patented Aug. 11, 1914.

Application filed November 12, 1913. Serial No. 800,594.

To all whom it may concern:

Be it known that I, MAURICE HERBERT COHEN, a citizen of the United States, residing at Brooklyn, in the county of Kings and State of New York, have invented new and useful Improvements in Combined Gas-Burners and Water-Heaters, of which the following is a specification.

The general objects of this invention are to 10 promote the efficiency of heat generated by a usual gas burner, and increase the utilization of the said heat. And to these ends the invention consists of a star-shaped burner provided with a water-back, whereby heat 15 escaping at the sides of the burner will radiate around the said water-back and so heat the water contained therein.

Other objects will appear and be better understood from that embodiment of my invention of which the following is a specification, reference being had to the accompanying drawings forming part hereof, in which:—

Figure 1 is a top plan view of the device. 25 Fig. 2 is a horizontal cross section taken on the line 2—2 in Fig. 3. Fig. 3 is a vertical cross section taken on the line 3—3 in Fig. 1. Fig. 4 is a vertical cross sectional view taken at right angles to Fig. 3. Fig. 5 is a 30 fragmentary top plan view of a modification of the face of the device.

The device, indicated in the drawings by *a* is constructed of one piece and thus may be formed of cast iron. It is adapted to be used 35 individually and can be also mounted in a usual gas range and form an element thereof.

Centrally located in the device *a* is a web- 40 burner 5 having on its upper surface the usual perforations 6 for the ignition of the gas. This burner is fed by a supply pipe 7, which is provided with the mixing chamber 8 for introducing the necessary air for pressure on the flame. The usual air pocket 9 45 is provided at the center of the burner; the plate 5' (see Fig. 4) may be detachable if desired for the purpose of cleaning the device when necessary.

In concentric spaced relation with the 50 periphery of the burner 5, is the wall 10, which coöperates with the wall 11 of the burner in forming the water-chamber 12. This wall 10 is provided at the inner side 55 with inwardly-directed radial arms 13, which are directed between the branches 14 of the burner 5; the reason of these and

being so positioned will be hereinafter fully explained.

At a suitable location on the wall 10, shown in the drawings at the rear, is an extended portion 15 for connection with the water-pipes 16 and 17, and separating the pipes in the interior of the water-chamber is a wall 18. The pipe 17 is the inlet or cold water supply pipe and being located 60 adjacent to the floor 19, directs the water along the bottom of the chamber 12. As the water becomes heated adjacent to the top of the chamber it passes out through the outlet or hot water pipe 16; this pipe is located adjacent to the top portion 20 of the heater, and connects the water chamber with the storage tank (not shown).

As shown in Fig. 1 the upper face 20 of the chamber 12 is provided with concentric 75 corrugations 21 and 22, which coöperate with a vessel placed on the burner to pocket the heated air and increase the efficiency of the flame. It will be noted that a kettle or a like vessel would rest upon the usual grating 80 (not shown) located above the burner, thus permitting a space to remain between the bottom of the kettle and the crest of the corrugations; and the heat arising from the flame in the burner 5, will radiate along the 85 bottom of the kettle and passing over the corrugations, will be pocketed therebetween.

Lugs 22' are provided at the bottom of the device and function as legs for the same.

As shown in Figs. 2 and 4, the lower portions of the chamber at either side, are concaved as at 23. These concave portions run parallel with the longitudinal axis of the device and are substantially straight in direction. These concave portions are provided so that pipes may be accommodated at the sides of the device and fit snugly against the same. This is essential in the case where a series of the burners or heaters are mounted on a gas range, which has a 90 limited surface space. And so that the pipes connected to the rear burner will not conflict with the front burners, the concave parts allow the pipe to pass as shown in dotted lines in Figs. 2 and 4.

A modification of the top surface 20 is shown in Fig. 5. In this case the corrugations are radially disposed and allow the heated air to pass over the corrugations and so heat the water in the chamber.

In operation the device may be used singly or collectively as hereinbefore stated,

but is especially adapted to be fitted in a gas range. The pipe 7 is connected to a gas-supply pipe not shown, and the inlet water pipe 17 is connected to the cold water supply pipe. Likewise the pipe 16 connects the water chamber 12 with the storage hot-water tank or boiler. The water enters the chamber at 24 (see Fig. 3) and circulates around the branches of the burner. The plates 13 direct the water in a zigzag motion, and as the water travels it becomes heated by the heat-waves radiating along the top surface 20 of the chamber. It will be seen that the upper portion of the water will be heated and as the outlet pipe 16 is located uppermost the heated water passes therethrough to the tank or boiler.

It is to be understood that the burner may be adapted to use natural or artificial gas. It may be adapted also to use the usual acetylene gas now used in a large number of farms and dwellings.

It is obvious that those skilled in the art may vary the details of construction and arrangements of parts without departing from the spirit of my invention and therefore I do not wish to be limited to such features except as may be required by the claims.

30 What is claimed as new is:

1. In a device of the class described, a burner and a water-heating chamber formed

integral therewith, the top portion thereof having concentric corrugations of different heights substantially as described.

2. In a device of the class described, a burner having radial arms, a water-heating chamber surrounding the burner and formed integral therewith, and deflectors positioned on the inner peripheral wall of the chamber so as to direct the water into between the arms of the burner for the purposes set forth.

3. A combined gas burner and water heater, comprising an outer casing adapted for connection to an inlet pipe and an outlet pipe and forming the outer wall of a water chamber, a burner proper disposed centrally of the casing and provided with radial arms forming the inner wall of the water chamber, said water chamber being interiorly divided into communicating compartments, and said outer casing being formed with radially disposed baffles arranged in staggered relation with the arms of the burner and coöperating with the said arms for the purpose set forth.

In testimony whereof I affix my signature in presence of two witnesses.

MAURICE HERBERT COHEN.
